DESCRIPTION

U.S. PATENT DOCUMENTS

D35,165 S *	10/1901	Williams	.....	D9/544
D36,781 S	2/1904	Blower		
D155,868 S	12/1948	Braun		
3,405,831 A	10/1968	Hudson		
3,468,648 A	9/1969	Nowak		
3,792,988 A	2/1974	Nowak et al.		
3,956,441 A	5/1976	Uhlig		
4,105,428 A	8/1978	Adams		
4,170,622 A	10/1979	Uhlig		
D335,455 S	5/1993	Brown		

FIG. 1 is a perspective view of a container neck showing our new design, with a container body and a container neck finish being shown in broken lines for environment only and forming set part of the claim.

FIG. 2 is a front elevational view of the container neck in FIG. 1, the rear elevational view and the side elevational views being identical to FIG. 2.

FIG. 3 is a sectional view taken along the line 3-3 in FIG. 2; and,

FIG. 4 is a sectional view taken along the line 4-4 in FIG. 3. The dashed-dot-dashed lines define the boundary lines of the claimed design. The broken lines shown in the figures are included for the purpose of illustrating environmental elements only and form no part of the claimed design.
